J. B. MCCLAIN,
SOFT METAL FURNACE,
APPLICATION FILED AUG. 16, 1920.

1,362,429.

Patented Dec. 14, 1920.

UNITED STATES PATENT OFFICE.

JOHN B. McCCLAIN, OF BROOKLYN, NEW YORK.

SOFT-METAL FURNACE.

1,362,429.

Specification of Letters Patent. Patented Dec. 14, 1920.

Application filed August 18, 1920. Serial No. 403,703.

To all whom it may concern:

Be it known that I, JOHN B. McCCLAIN, a citizen of the United States, and a resident of the city of New York, borough of Brooklyn, in the county of Kings and State of New York, have invented a new and Improved Soft-Metal Furnace, of which the following is a full, clear, and exact description.

10 This invention relates to furnaces and especially to furnaces for melting or reducing certain ores or metals that are not overly refractory.

15 Among the objects of the invention is to provide a furnace of novel design having peculiar merit for the reducing or melting of aluminum, Babbitt metal, solder, or other analogous soft metals.

20 Another object of the invention is to produce a furnace for melting metal in which the flames and other products of combustion are caused to pass through or over the bowl or other member which serves to hold the material being treated.

25 Another object of the invention is to improve the general construction of the furnace with respect to the drum portion through which the operator has access to the metal, the stack connection, the means 30 for supplying a force of fresh air through the fire box, and to the means adapting the furnace so as to be provided with means for pouring the molten metal directly from the bottom of the bowl, especially in the 35 larger types.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which— 45 like reference characters designate the same parts in the several views, and in which—

Figure 1 is a vertical sectional view of my improvement.

Fig. 2 is a horizontal section on the line 50 2—2 of Fig. 1.

Fig. 3 is a vertical sectional view of a variation in the furnace respecting the means for pouring molten metal from the bowl, the view corresponding otherwise to 55 the central portion of Fig. 1.

Referring now more particularly to the

drawings I show my furnace as comprising any suitable base 10 built in or supported upon a foundation 11 of concrete or the like, the base plate 10 being located beneath the surface of the foundation which may be regarded as the floor of the furnace room. Supported directly upon the base 10 is an annular member 12 of L-shape in cross section and with which co-operates an inner annular member 13. The space 14 between the two annular members 12 and 13 serves as an inlet for a forced draft which may be delivered to any desired portion of the space 14, as through a pipe 15. The member 13 is provided with radially formed holes 16 through which the blast of fresh air is admitted into the interior of the ring 13 for delivery upward through a grate support 17 and between the grate bars 18 supported thereon. On any desired side of the furnace is provided an ash pit or clean-out 19. The grate support 17 rests directly upon the ring 13.

The shell or body 20 of the furnace may be of any suitable size, structure, or design, but shown as being in the form of a vertical cylinder and lined with fire brick 21 or other suitable refractory material. At one side the shell is provided with a suitable fuel door 22, which likewise may be lined with fire brick, if desired. This fuel door is made as nearly air and gas tight as may be practicable. The interior of the body, especially the lower half, constitutes a fire box.

The bowl, known in the art as the accelerator bowl, is indicated at 23, the same being approximately semi-elliptical in form and provided at its upper open end with an outwardly projecting flange 24 through which the bowl is supported upon the upper end of the body 20. The shape of the bowl provides that the main portion thereof is suspended within or toward the fire box and is nearly all spaced from the fire brick lining. Except as otherwise explained the bottom of the bowl is imperforate and so is adapted to hold the metal to be reduced or melted. Obviously the bowl will be made of semi-steel or some other refractory material.

Extending upward from the top of the shell 20 and conforming thereto is a drum 25 through one side of which is formed an opening 26 which may be termed the work door or through which access may be had

to the bowl for introducing metal, stirring, or otherwise treating the metal, or for withdrawing the metal from the bowl. The opening 26 is normally closed by a pair 5 of doors 27.

The bowl is provided with a series of radial holes 28 formed through the upper portion at any desired level and above the level of the metal as may be understood 10 from the dotted line 29. These holes 28 are formed on all sides of the bowl except on the side adjacent to the work door, as plainly indicated in Fig. 2.

The drum 25 is surmounted with any 15 suitable dome 30 constituting the base of a stack or a means serving to direct the products of combustion upward through a stack. Supports 31 are connected to the dome to relieve the weight of the dome or 20 any part supported thereon from the furnace, and especially the drum 25, which latter is detachably connected as by lag screws 32 to the flange 24 of the bowl. It will thus be seen that the drum may be removed or 25 interchanged without disturbing either the dome or any other part of the structure. When the drum is detached the bowl may be hoisted out of the body and replaced either by a bowl of the same construction 30 or one of a different construction.

Fig. 3 indicates the type of bowl I prefer to use in connection with the large furnace designs, especially when the molten metal is desired to be drawn off in a stream from 35 the bottom of the bowl. This bowl is indicated at 23' and is provided with a nozzle 33 with the bore of which communicates a spout 34 leading to the outside of the body or shell. The plug normally closing the 40 port 33' comprises a screw 35 having a ball-shaped end 35' at the bottom of the bowl. The shank portion of this screw is fitted in a threaded extension 36 at the top of the bowl, and at the upper end of the screw 45 is a removable wheel or handle 37 which under normal conditions is hung up in the furnace room outside of the furnace and which the operator may slip upon the upper end of the screw when he desires to 50 rotate the same for opening or closing the port 33'. The other parts of the furnace are to be understood as being constructed substantially as already set forth.

The operation of the furnace may be 55 briefly summarized as follows: Blocks or sticks of metal or the like to be fused or melted are delivered into the bowl through

the doorway 26 of the drum, fuel will be admitted into the fire box through the door 22 and after being kindled will be caused 60 to burn at high temperature by means of a forced draft introduced through the pipe 15, channel 14 and holes 16, and thence upward through the grate 18. The products of combustion pass well around all that 65 portion of the bowl which holds the metal and thence passes through the holes 28 and over the top of the molten metal. Since there is no hole 28 provided beneath the work door the operator is relieved from 70 direct contact of any flame or gases that otherwise would reach him at this point while reaching in through the work door when desired. The molten metal may be ladled out through the work door, or as 75 above intimated the metal may be poured out through the nozzle and spout, as shown in Fig. 3, when the plug 35 is turned upward.

I claim:

1. In a furnace for melting aluminum or other soft metals, the combination of a furnace body providing a fire box, a bowl supported above the body and having a portion projecting downward into the body 85 and spaced therefrom, and means to cause the products of combustion from the fire box to pass through the wall of the bowl, and over the metal in the bowl.

2. A device as set forth in claim 1 in 90 which the bowl is provided with a series of holes formed therethrough adjacent to its open upper end.

3. A device as set forth in claim 2 in 95 which holes are formed at about the same level, and the series of holes is complete except at one side of the bowl.

4. In a soft metal furnace as set forth in claim 3 in which there is provided a drum extending upward from the body and 100 top of the bowl, the same being provided with a work door on the side where the series is interrupted.

5. The herein described soft metal furnace having a base comprising a pair of 105 concentric rings, one of which is angular in cross section providing a draft channel, the inner ring being provided with air holes through which the draft of air from the channel is admitted within the rings, and 110 a fire box located above and supported upon said base.

JOHN B. McCALAIN.
